To all whom it may concern:

Be it known that I, CHARLES P. McDougall, a citizen of the United States, residing at Frankfort, in the county of Clinton and State of Indiana, have invented a new Design for a Paneled Portion of Articles of Furniture, of which the following is a specification, reference being had to the accompanying drawing, forming part hereof.

The single figure of the drawing is an elevation of a paneled portion of an article of furniture, showing my new design. This design is for a portion of furniture having two panels, an upper panel A and a lower panel B, these two panels being different from each other in appearance, the lower panel being of the same general appearance as the framing, and the upper panel consisting of a plate of transparent material, such as glass, having a backing of ornamented opaque material.

I claim:

The ornamental design for a paneled portion of articles of furniture, as shown and described.

In witness whereof, I have hereunto set my hand at Frankfort, Indiana, this 9th day of February, A. D. one thousand nine hundred and fifteen.

CHARLES P. McDougall.
